UNITED STATES PATENT OFFICE.

JAMES H. CRITCHETT, OF NIAGARA FALLS, NEW YORK, ASSIGNOR TO ELECTRO-METALLURGICAL COMPANY, OF NIAGARA FALLS, NEW YORK, A CORPORATION OF WEST VIRGINIA.

FLEXIBLE CONNECTION FOR ELECTRIC FURNACES.

1,331,625.

Specification of Letters Patent. Patented Feb. 24, 1920.

Application filed July 19, 1919. Serial No. 312,044.

To all whom it may concern:

Be it known that I, JAMES H. CRITCHETT, a citizen of the United States, residing at Niagara Falls, in the county of Niagara and State of New York, have invented certain new and useful Improvements in Flexible Connections for Electric Furnaces, of which the following is a specification.

The present invention relates to electric furnaces and more particularly to electric connections for conducting the current to the electrodes.

In the construction of electric furnaces it is necessary to provide a flexible connection between the electrode and source of power in order to allow movement of the electrode to take care of changes in the level of the furnace and wear of the electrode. This flexibility is usually obtained by the introduction of a short section of conductor made up of the necessary number of flexible copper cables. In small furnaces which require moderate currents no difficulty is found in providing flexible cables of sufficient current carrying capacity, but in the modern large plants which require a very large current, difficulties are encountered due to the mutual inductive effect of these cables. The addition of more cables does not increase the current carrying capacity, of the system in proportion to the copper added owing to the increased inductive effect mentioned.

The mutual inductive effect in other parts of the circuit may be reduced by interlacing the outgoing and return conductors, but it is difficult to interlace bars of different polarity beyond the point where the flexible connection starts. There is therefore an appreciable drop in the power factor due to this non-interlaced condition in the flexible connection.

It is the principal object of this invention to provide means for reducing the mutual inductive effect and conversely increasing the power factor of the system.

I accomplish this object by so disposing the elements of the flexible connection relatively to each other that the electro-magnetic effect upon each other is considerably reduced.

In order to more fully explain the principle upon which the invention is based and to indicate one way in which the invention

may be advantageously carried into practice, I refer to the accompanying drawings in which—

Figure 1 is a diagrammatic view of a device of ordinary construction representing the prior art;

Fig. 2 is a similar view of a device embodying the invention;

Fig. 3 is a diagrammatic view of the usual electrical connections between a single-phase furnace and a source of supply; and

Fig. 4 is a similar view embodying the invention.

In Fig. 1—10 represents a source of alternating current as for instance a transformer, 11 a set of rigid busbars, 12 a flexible connection composed of a number of flexible cables and 13 the movable electrode.

The busbars, as has been previously mentioned, are in practice interlaced, *i. e.* a bar of one polarity is adjacent a bar of relatively opposite polarity, whereby the mutual inductive effect is neutralized. However, the interlacing cannot be practically continued beyond the point 11' where the flexible connection begins. At this point the flexible cables making connection between the bus bar or bus bars of one polarity and the movable electrode separate from connectors of opposite polarity and form a separate group. Under these conditions the magnetic lines surrounding one cable continuously cut each or most of the other cables and thereby set up, as is well understood in these other cables an electromotive which in its effect neutralizes part of the current flowing therethrough and this effect increases progressively with the number of cables.

In Fig. 2 is shown a simple arrangement for reducing this mutual inductive effect. One half of the cables of the flexible connection 12' are carried on an insulated support 14 which is yieldingly held in spaced position relatively to the remaining cables by means of a rope or cable 15 running over pulleys 16 and a suitable counter weight 17. By this arrangement the one set of cables is maintained in proper relation to the other set of cables and yet allowed freedom of movement.

It is understood that the flexible connection may be divided in more than two groups and that the yielding spacing rela-

tion may be effected in other ways and by other means. I have referred to the counter weight-operated support merely as one simple and convenient means for carrying out 5 the object and contemplate the use of all means whereby one cable or group of cables is maintained in spaced relation relatively to another cable or other cables in such a way that the normal function of the flexible 10 connection as a whole is not materially impeded.

In Fig. 3, which represents the prior art, the bus bars 20 and 20' of relatively opposite polarity are interlaced in the usual 15 manner between the transformers 21 and the flexible connections. At the end of the bus bars the flexible connection 22 leads from the bus bars 20 to the electrode 23 and the flexible connection 22' leads from the 20 bus bars 20' to the electrode 23', 24 representing the furnace shell.

Fig. 4 shows a similar arrangement to which the invention is applied. By means of the counter weights 25 and ropes or 25 cables 26 one group of cables of the flexible connections 22 and 22' respectively is held yieldingly in spaced relation from the other group.

I claim:

30 1. In an electric furnace having a movable electrode, a flexible connection composed of a plurality of flexible conductors

and means for minimizing the effect of mutual inductance between said conductors.

2. In an electric furnace having a movable electrode, a flexible connection composed of a plurality of flexible conductors and means for yieldingly holding some of said conductors in spaced relation relatively to others of said conductors. 35

40 3. In an electric furnace having a movable electrode, a flexible connection composed of a plurality of flexible conductors having their end portions fixed relatively to each other and means for yieldingly holding the said intermediate portions in spaced relation. 45

4. In an electric furnace having a movable electrode, a flexible connection composed of a plurality of flexible conductors 50 and yielding means connected to some of said conductors and operative to draw them in a direction away from others of said conductors.

5. In an electric furnace having a movable electrode, a flexible connection composed of a plurality of flexible conductors and means including a pulley, rope and counterweight for yieldingly spacing some of the said conductors from others of said 60 conductors. 55

In testimony whereof, I affix my signature.

JAMES H. CRITCHETT.
